EGG CUP OR SIMILAR ARTICLE

Constance Ray White, Beverly Hills, Calif.

Application October 26, 1951, Serial No. 17,135

Term of patent 7 years

(Cl. D44—9)

To all whom it may concern:

Be it known that I, Constance Ray White, a citizen of the United States of America residing at Beverly Hills, in the county of Los Angeles and States of California, have invented a new, original, and ornamental Design for an Egg Cup or Similar Article, of which the following is a specification, reference being had to the accompanying drawing, forming part thereof.

In the drawing

Fig. 1 is a side elevational view of an egg cup, showing my new design;

Fig. 2 is another side elevational view taken at right angles to Fig. 1; and

Fig. 3 is a top plan view thereof.

I claim:

The ornamental design for an egg cup or similar article, substantially as shown.

CONSTANCE RAY WHITE.
